(57) **CLAIM**

The ornamental design for a tape for a tape printer, as shown and described.

DESCRIPTION

FIG. 1 is a front view of a tape for a tape printer;

FIG. 2 is a top view thereof;

FIG. 3 is a right-side view thereof;

FIG. 4 is a left-side view thereof;

FIG. 5 is a rear view thereof;

FIG. 6 is a bottom view thereof; and,

FIG. 7 is an enlarged sectional view thereof taken along the line 7—7 of FIG. 5.

The broken line showing is for illustrative purposes only, and forms no part of the claimed design.

The broken away showing in FIGS. 1, 2, 5 and 6 indicates that the tape for a tape printer is of indeterminate length.
